UNITED STATES PATENT OFFICE.

JOHN S. WHITE, OF WILMINGTON, DELAWARE, ASSIGNOR TO LILLY B. SMITH, OF ATLANTA, GEORGIA.

PORTABLE HOUSING DEVICE.

1,416,146.

Specification of Letters Patent. Patented May 16, 1922.

Application filed November 26, 1920. Serial No. 426,397.

To all whom it may concern:

Be it known that I, JOHN S. WHITE, a citizen of the United States, residing at Wilmington, in the county of New Castle and State of Delaware, have invented certain new and useful Improvements in Portable Housing Devices, of which the following is a specification.

One object of my invention is to provide an improved portable housing device which can be easily moved from place to place and can be used with great comfort and convenience at the seashore, for camping purposes, on open porches or for many other purposes where a person wishes privacy in a portable housing device without the deprivation of the comforts and conveniences procurable in a permanent housing structure and at the same time affording an abundance of fresh air and other conditions which will insure health.

Another object is to so construct my improved device that it will insure privacy and comfort as a sleeping compartment or as a couch so that a person may either sit upright therein or in an inclined position and at the same time will be protected against the elements.

Another object is to so construct my invention that when used for sleeping purposes, sufficient fresh air can be admitted into the structure without causing drafts or other conditions which would impair the health of the occupant.

A further object is to include in the structure, means readily adapted for use in storing either personal or bed clothing; said means being operative to prevent drafts from affecting the sleeper. Said means also when not adapted for use for the latter mentioned purpose being operative to provide a back support for a person sitting within the device.

A still further object is to provide means normally invisible but which are readily accessible for toilet purposes.

Another object is to construct my improved device in such manner that it will be ornamental and pleasing in appearance and will be so designed as to permit the ready cleaning of the various parts.

A still further object is to make the device of my present invention of a durable construction which can be used in all kinds of weather and at the same time insure comfort to the user.

These objects, and other advantageous ends which will be described hereinafter, I attain in the following manner, reference being had to the accompanying drawings in which—

Figure 1 is a front elevation of a portable housing device made in accordance with my present invention.

Figure 2 is a transverse sectional elevation taken on the line 2—2 of Figure 1.

Figure 3 is a view of the same general character as shown in Figure 2 with certain of the parts having been moved into another position.

Figure 4 is a longitudinal sectional elevation taken on the line 4—4 of Figure 2.

Figure 5 is a front elevation showing the device full open in the front.

Figure 6 is an end elevation of the device open at the front; the movable sections serving as a canopy.

Figure 7 is a fragmentary rear elevation illustrating an opening closed by a door to permit a waste water receptacle to be removed and inserted therein, and

Figure 8 is a section on the line 8—8 of Figure 4.

Referring to the drawings, 8 represents a hollow body portion which may be made of any suitable material such as sheet metal, wood or the like; said body portion being elongated in the direction of its width and including a partition 9 spaced inwardly a short distance from the end 10; said partition extending upwardly from the bottom 11 to the top 12 as clearly shown in Figures 2, 3 and 4. The space between the partition 9 and the end 10 is divided into a number of compartments 13, 14, 15, 16 and 17. The bottom 11 supports, within the main compartment or chamber 18, a frame 19; said frame stopping short of the partition 9 and of the opposite end 20 of the body portion. A cushion 21 is positioned upon the frame 19 and is substantially of the same length as said frame as shown in Figure 4. This

cushion extends from the front 22 to the back 23 of the body portion 8 and provides a bed bottom and is preferably tufted and covered with material which presents a pleasing appearance. Two end cushions 24 and 25 are placed in upright positions; the lower ends being respectively positioned adjacent the ends of the frame and rest upon the bottom 11. A ledge strip 26 is secured 5 to the partition 9 and end 20 and also to the back 23 at a position just above the top edges of the cushions 24 and 25. The part 27 of the ledge 26 which is secured to the back 23 has hinges 28 secured thereto at positions 10 spaced apart within the width of the chamber 18 and these hinges are attached to one edge of a box 29; said box flaring from its end 30 to its end 31 and being normally positioned as shown in Figure 2 with its side 32 15 positioned against the back 23 of the body portion 8 so that its opposite side 33 slants downwardly and forwardly from the hinges 28. The side 33 has a cushion 34 which provides a back cushion, as clearly shown in 20 Figures 2 and 4, to permit a person to sit on the cushion 21 with his or her back supported by the cushion 34 when the front section is open as shown in Figures 5 and 6. The open end 31 of the box 29 is closed by 25 a door 35; said door being hinged to the outer free end of the side 33. When in this lowered position, the end 30 of the box 29 is positioned under the portion 27 of the ledge strip 26 so that an ornamental finish is 30 provided by the strip 26 which covers the upper end of the box 29 and also the upper edge portions of the end cushions 24 and 25. The box 29 can be swung upwardly either in the 35 position shown in full lines in Figure 3 or into the position shown in dot-and-dash lines in said figure. When in the position shown in full lines in Figure 3, the box can be supported by means of a hook 36 which is 40 adapted to engage within an eye 37 on the box. If desired similar structures can be provided at opposite ends; the one hook 36 being preferably secured to the partition 9 as shown in Figure 2. When in this position, the door 35 can be readily opened to permit 45 clothing, either bed clothing or personal clothing, to be stored within or removed from the interior of the box 29 and by raising said box on its hinges a greater area of the cushion 21 will be exposed for sleeping 50 purposes. The back 23 is provided with screened windows 38 at a position above the ledge strip 26 and I preferably provide flexible curtains 39 which are slidably mounted on rods 40 so that the curtains can be drawn 55 in position to secure privacy and also to vary the amount of ventilation through the screened windows. It will be noted that by swinging the box 29 into the dot-and-dash line position shown in Figure 3, that said 60 box will serve as a baffle or air entering

through the screened windows 38 and when the box is in the full line position as shown in Figure 3, the same will form a canopy or overhead structure to protect the sleeper against downward draft and furthermore 70 the curtains 39 can be moved into a position away from the screened windows and yet the box 29 will serve as means for preventing the sleeper from being seen through said windows. The box 29 can be held in the dot-and-dash line position by means of a hook 75 41 which is adapted to engage with the eye 37; said hook 41 being positioned above and to the rear of the hook 36.

The front 22 has an opening 42, the bottom of which is preferably made slightly below the top of the forward edge of the cushion 24. This opening extends preferably the full width of the chamber 18 and can be closed by two screened frames 43 and 44 which are hinged together at 45; the upper frame 43 being hinged at 46 to the lower edge of the top 12; said top being of a curvature such as clearly shown in Figures 2, 3 and 8. 80

I preferably provide curtains 47 for the screened frames 43 and 44; said curtains being slidable on rods 48. The frames can be held in their closed position by any suitable securing means accessible from the interior of the chamber 18 and as illustrated 90 I have shown hooks 49 for said purpose. With this arrangement the frames 43 and 44 can be extended into their full open positions as shown in full lines in Figure 6 and 100 supported by auxiliary bracket bars 49^a; said bracket bars having their lowered ends secured to the body portion 8 in any suitable manner preferably by inserting them within sockets 50 as shown in Figure 6; the upper 105 ends of the bars 49^a being hooked within eyelets 51 in the frame 44.

For purposes of protection during a storm or severe weather, I provide a covering 52 which may be in the form of oil or processed 110 cloth which is wound upon a roller 53 under the bottom 11 of the body portion; said covering being adapted to be drawn up over the back and top and secured by means of cleats 54 which are adapted to be projected through 115 eyelets in the edge of the covering 52. If desired an auxiliary covering 55 can be attached in front of the closed frames 43 and 44 as shown in Figure 3 with the top edge of the covering 55 underlapping the covering 52 and also attached to the cleats 54. The bottom of the covering 55 can be secured 120 to cleats 56 on the front 22 below the bottom of the opening 42.

The body portion 8 can be mounted on 125 rollers or wheels 57 which are preferably secured to the bottom of tubular end supports 58; said end supports being bent in the form of yokes and bolted to the opposite ends of the body as clearly shown in Figure 130

6. If desired the roller 53 for the covering 52 can be constructed in the same manner as a spring shade roller so that it will automatically operate to re-wind the covering 52 5 when it is desired to remove said covering from its protecting position.

The partition 9 has an opening 60 which is normally closed by a panel 61; said opening and panel in their normal positions being 10 directly behind the cushion 24 so as to be invisible when the cushion 24 is in place. The panel or door 61 is hinged at its bottom to the partition 9 and when the cushion 24 is removed, by slightly tilting and lifting the 15 same, the panel can be swung into the dot-and-dash line position shown in Figure 4. The inner surface of the panel 61 supports a lavatory 62 and in order to support the lavatory in a horizontal position, I provide 20 a flexible connection which consists of two bars 63 and 64 which are hinged together at 65; the bar 64 being pivoted to the panel 61 while the bar 63 is pivoted at 66 to a fixed part on the end 10. The lengths of the bars 25 63 and 64 are such that when the panel moves into its horizontal position as shown in dot-and-dash lines in Figure 4, said bars will form a brace for supporting the panel and lavatory in a horizontal position so that 30 the same can be used for washing purposes. The lavatory 62 includes a recessed lip 67 and the bottom of the compartment 13 has a waste water receptacle 68 so positioned that after the device is used, the mere swinging 35 of the panel 61 upwardly on its hinge will cause the lip to be projected downwardly so that the waste water within the lavatory will fall into the receptacle 28. This receptacle can be removed from time to time through an 40 opening 69 in the back 23; said opening being normally closed by a door 70 as shown in Figure 7. Clean water can be supplied to the lavatory through the medium of a pipe 71 which leads from a water storage tank 72 45 which is mounted within the compartment 13 and, as shown, the tank 72 has a filling neck which leads through the top 12 of the body portion and through which fresh water can be supplied from time to time.

50 The pipe 71 is provided with a valve 73 which may be operated from the compartment 14; said compartment having an opening 74 closed by a door 75. The outlet end of the pipe 71 is so positioned that when 55 the valve 73 is opened, the water will flow into the lavatory 62 and in this manner a person within the chamber 18 can conveniently wash, and when not desired for use the lavatory can be moved into the compartment 13 merely by swinging the panel 61 upward as above described, after which the cushion 24 can be slipped into place between the frame 19 and partition 9. I 60 preferably provide a mirror 76 which is positioned within the compartment 14 and se-

cured to the inner surface of the end 10 of the body portion; said mirror being in position so as to be clearly visible through the opening 74 in the partition 9 when the door 75 is opened. The compartment 16 can be 70 used for an electric storage battery for the purpose of supplying current to electric lamps 77.

The compartment 17 extends to the rear of the compartment 14 and is located between 75 the compartment 16 and the compartment 13; there being an extension 17^a of the compartment 17 which leads downwardly to the rear of the compartment 13 as clearly shown in Figure 8. The compartment 17 80 has an opening 78 which is normally closed by a hinged door 79 and the extension 17^a of the compartment 17 has an opening 80 which is closed by a hinged door 81. The compartment 17 can be used preferably for 85 holding coats or other articles to prevent them from being mussed and by the provision of the extension 17^a it is possible to suspend any long garments, such as men's trousers or the like; said garments extending entirely within the depth of the compartment 17 and its extension 17^a. The door 80 can be opened to permit shoes or similar articles to be stored in the bottom of the extension compartment 17^a. 90

Thus a person can comfortably sit, recline or sleep within the device and at the same time can wash and keep his or her clothes in proper order. A casing 82 is 100 preferably secured to the bottom 11 and may be used for storing bed clothing or other articles.

It is believed to be obvious that my improved device affords exceptional comfort and convenience which renders the device 105 particularly desirable for use out of doors such for example as the seashore, for camping purposes or the like and at the same time the structure is such that it can be readily moved from place to place to suit 110 the convenience and pleasure of the occupant.

While I have described my invention as taking a particular form, it will be understood that the various parts of my invention may be changed without departing from the spirit thereof, and hence I do not 115 limit myself to the precise construction set forth, but consider that I am at liberty to make such changes and alterations as fairly 120 come within the scope of the appended claims.

Having thus described my invention, what I claim as new and desire to secure by Letters Patent is:—

1. A portable housing device including a body portion providing a chamber; a bed bottom therein; a box hinged adjacent the back of said body portion and adapted to be swung from a position partly covering 130

- the bed bottom into a position spaced above the bed bottom, said box having an opening in its bottom; a door for closing said opening; and means for locking said door 5 to prevent it from opening downwardly when the box is in said first position; substantially as described.
2. A portable housing device including a body portion providing a chamber; a bed bottom therein; and a back member movable from a position covering a portion of the rear of the bed bottom into a position spaced above said bed bottom to form a canopy for a person lying on said bed bottom; substantially as described.
3. A portable housing device including a body portion providing a chamber; a bed bottom therein; and a box movable from a position covering a portion of the rear of 20 said bed bottom to a position spaced above said bed bottom, said box flaring downwardly whereby when the box is in said first position its outer side will be inclined to the plane of the bed bottom; substantially 25 as described.
4. A portable housing device including a body portion providing a chamber; a bed bottom therein; and a box providing a seat back and movable from a position partly 30 covering the bed bottom into a position spaced above the bed bottom, said box having an opening which permits access to the interior thereof when in said raised position; substantially as described.
5. A portable housing device including a body portion providing a chamber; a bed bottom therein; and a box movable from a position covering a portion of the rear of 35 said bed bottom to a position spaced above said bed bottom, said box flaring downwardly whereby when the box is in said first position its outer side will be inclined to the plane of the bed bottom, the wide end of said box having an opening whereby free 40 access may be had to the interior of the box 45

when the box is in its raised position; substantially as described.

6. A portable housing device including a body portion providing a chamber; a bed bottom therein; and a box hinged adjacent 50 the back of said body portion and adapted to be swung from a position partly covering the bed bottom into a position spaced above the bed bottom, said box having an opening which permits access to the interior 55 thereof when said box is in its raised position; substantially as described.

7. A portable housing device including a body portion providing a chamber and windows leading therefrom; a bed bottom in 60 said chamber; and a back member movable from a position covering a portion of the rear of the bed bottom into a position spaced above said bed bottom to form a canopy spaced between said bed bottom and said 65 windows; substantially as described.

8. A portable housing device including a body portion providing a chamber and windows leading therefrom; a bed bottom in 70 said chamber; and a back member movable from a position covering a portion of the rear of the bed bottom into a position spaced above said bed bottom to form a canopy spaced between said bed bottom and said 75 windows, the forward portion of said member when in said latter position being spaced to the rear of the front of said chamber whereby air can pass from said windows to a position below the level of said member but a person lying on said bed bottom 80 cannot be seen through said windows; substantially as described.

In testimony whereof I have signed my name to this specification in the presence of two subscribing witnesses.

JOHN S. WHITE.
